UNITED STATES PATENT OFFICE.

FREDRICK H. AULD, OF COLUMBUS, OHIO, ASSIGNOR TO THE D. L. AULD COMPANY, OF COLUMBUS, OHIO, A CORPORATION OF OHIO.

NAME PLATE AND METHOD OF PRODUCING IT.

Application filed December 4, 1925. Serial No. 73,150.

This invention relates to an improved article of manufacture consisting of a composite name, number or label plate, and of the method of producing the same.

5 The first part of my invention consists of a new article of manufacture comprised of a name, number or label plate of composite construction being formed of a base of wood, a covering or top layer also of wood, and a filling or intermediate plate of metal suitably united to the wood base and having its characters, as numbers, names or designs protruded through the top layer so as to present metallic lines forming such 10 characters to view in contrast with the surrounding field of wood selected for the beauty of its grain and capacity to receive a high or polished finish.

This composite plate has various uses 20 being in the nature of a label applicable to different articles of manufacture to designate the quantity thereof or the name and address of the manufacturer or other suitable information desirable to expose to 25 view.

The second part of my invention relates to the method of producing this composite plate, and consists in the following major steps:

30 The fabrication of the design, letters, numbers, or names, as the case may be on the metal plate, as by the use of suitable dies adapted to strike-up the plate with the appropriate configurations.

35 The fabrication of a wood base in the nature of a thick veneer.

The fabrication of the top or face of wood also in the nature of a veneer.

40 The application of pressure to embed the metal plate into the base of wood, and to also embed the top layer into the recesses that surround the tracery or lines that form the indicia on the metal plate.

45 The planing or abrading off the shattered portions of the upper layer to leave only those parts which have entered into and filled such recesses; and incidentally in polishing the metallic tracery of the indicia where it is exposed through the top layer.

50 I prefer also the further steps of the application of cement or some suitable adhesive between the metal plate and the base plate to make the metal plate the more readily adhere to the base plate; and the appli-

cation of a similar adhesive to the recesses 55 between the lines of tracery to make the upper layer more readily adhere to the recesses.

In the drawings:

Figure 1 is a plan view of a strip of wood 60 from which the wood base is made, with a metal plate placed thereon;

Figure 2 is a like view but with the upper layer of wood applied over the metal plate, 65 with the metal plate shown in dotted lines;

Figure 3 is a longitudinal sectional view of the several plates before pressure is applied to unite them;

Figure 4 is a like view showing the plates 70 after the application of pressure;

Figure 5 is another like view after the planing or polishing step has been performed;

Figure 6 is a plan view of the completed 75 article.

Referring first to the composite plate which constitutes my new article of manufacture the numeral 1 designates a strip of wood in the nature of a veneer, though of greater thickness than usual in veneer sheets. This base will preferably be made from wood of an ornamental character such as mahogany, walnut, birds-eye maple, or the like so that it will be capable of receiving 80 a high finish and of taking on a hand, 85 some appearance.

The next element of my composite article consists of a metallic or alloy plate, preferably brass indicated at 2. This plate may be of any outline, though in the present 90 case I have fashioned it into the form of a disc. It is subjected to the operation of suitable dies or other means of forming thereon such design, lettering or numbering as may be desired for the particular use. 95 In the present case I have formed a series of circular beads or raised portions indicated at 3 which leaves between each two beads recesses or depressed portions 4 and likewise within the inner bead as indicated 100 at 5.

After the metal plate is so fashioned I place it upon the wood base of thick veneer. I prefer to use cement or some form of adhesive between the wood base and the metal plate to more firmly unite them. I also prefer to apply a like adhesive to the recesses and the walls thereof for the like 105

purpose of more readily securing together the metal plate and the upper layer.

Having done all this I apply the upper layer, itself a strip of wood veneer as indicated at 6, to the upper face of the metal plate as seen particularly in Figure 3.

I then place the article so far fabricated in a suitable press, preferably a hydraulic press, and subject it to high pressure, say 1000 lbs. to the square inch, applying the pressure slowly. In this way I embed the metal plate down into the wood base and at the same time embed the upper layer down into the recesses and all about the outer edges of the metal plate as seen particularly in Figure 4. Where the two wood pieces come together I also apply some suitable adhesive.

The platen of the press which is brought into engagement with the upper layer 6 is configurated to agree with the design or indicia so that the pressure from it will be applied only to those parts of the upper layer which are over the recesses in the metal plate, so as not to mar the tracery of the design.

After the pressure step has been carried out long enough to insure the perfect embedding and adhering of the several plates together, I remove the product from the press. It is then in the condition shown in Figure 4. I now subject it to a grinding, planing or other character of abrasive action by which I remove the more or less shattered portions of the upper layer 6 until the layer is flush with the tracery of the design. Incidentally I polish off the tracery surfaces of the metal.

This finishes the product and results in a very handsome and permanent composite name or number plate applicable to various articles of commerce or produce.

Thus it will be seen that I have devised both a product and a method of producing it. I have described both concurrently as the best plan, as I believe, to make plain what the product is and the method by which it is produced.

These composite plates which as stated are to be used in the nature of labels, are generally produced on special orders so as to carry the particular indicia the particular user will desire.

Having thus fully described my invention,

what I claim as new and desire to secure by Letters Patent, is:—

1. The herein described article of manufacture consisting of a composite label plate composed of a wood base, a veneer top layer and a metal plate having elevated tracery and embedded in the base and having its depressed portions bordering its lines of tracery filled with and surrounded by said veneer top layer, the lines of tracery being exposed through such layer.

2. The herein described article of manufacture consisting of a composite label plate composed of a relatively thick wood base, a metal plate embedded therein and held by an adhesive and having indicia struck-up thereon, and a cover layer of wood veneer embedded within the recesses between the lines of tracery and held by an adhesive, the portions of the cover layer beyond the metal plate being also adhesively secured to the base, and the lines of tracery projected through the veneer top layer.

3. The herein described method of producing a composite label plate consisting in fabricating a wood base; in fabricating a metal design plate; in placing such plate upon the base; in fabricating a veneer cover; in placing such cover upon the upper face of the metal plate; in subjecting the whole to pressure sufficient to embed the veneer top layer into the recesses about the tracery of the design; and in dressing-off the shattered portions of the cover flush with the tracery.

4. The herein described method of producing a composite label plate consisting in fabricating a base of wood; in fabricating a design plate of metal; in applying an adhesive between the base and the metal; in fabricating a veneer cover; in placing such veneer upon the metal design plate; in applying an adhesive between the metal plate and the veneer cover; in subjecting the whole to pressure which acts against the veneer opposite the depressions between the lines of tracery of the metal plate and acts also on the veneer in the area outside of the metal plate; and in dressing-off the remaining projecting portions of the veneer above the metal plate to finish the same together with the tracery.

In testimony whereof, I affix my signature.

FREDRICK H. AULD.
